UNITED STATES PATENT OFFICE

2,459,802

AIR-CONDITIONING APPARATUS

Walter L. Fleisher, New City, N. Y.

Application November 6, 1944, Serial No. 562,190

4 Claims. (Cl. 183—45)

1

This invention relates to air-conditioning apparatus and more especially to capillary cells of the type illustrated in applicant's U. S. Patent No. 2,139,675.

In commercial embodiments of the capillary cell illustrated in said Patent No. 2,139,675, the layer of transversely arranged glass fibers at the entrance end of the cell is arranged on the inner side of the protective screen rather than on the outer side as shown in the patent. Rough handling, carelessness in shipping, hosing with steam or water or drastic cleaning all have a tendency to break down the structure of the commercialized capillary cell. The main difficulty arises from movement of the capillary fibers away from the sides of the casing allowing air and water to by-pass the contacting strands or from movement of the capillary fibers toward the side of the casing creating voids in the center section of the cell. While the transverse layers of capillary fibers at the entrance to and exit from the cell tend to maintain uniform spacing of the fibers by opposing the above referred-to movement of the fibers, such layers are so thin that the points of the glass strands projecting through the top and bottom layer are not held efficiently due more particularly to the top layer sagging in the middle. Also, cleaning of fluff or lint or the like collected on the outer surface of the transverse layers often resulted in breakage of the ends of the longitudinal strands, thereby destroying whatever support the transverse layer might have given.

An object of this invention is a capillary cell of the type above discussed which overcomes the disadvantages above referred to and provides efficient stabilization of the capillary threads not only when the glass fibers are of their initial length but also in the event that they become materially shorter than originally for any reason.

A further object is a capillary cell of the type above referred to of such arrangement that lint and the like collected at the entrance end of the cell may be removed therefrom with little or no damage to the capillary threads.

According to this invention, the capillary cell is provided with a stabilizing screen at its entrance as well as at its exit. Each screen is spaced inwardly from an extremity of the cell casing and each aperture of a screen receives a small group of capillary threads. These screens effect proper spacing of the main capillary threads and retain the spacing uniform throughout the life of the cell. Means are provided whereby the screen may be adjusted inwardly to compensate

2

for any reduction in the length of the fibers which may develop from use of the cell or cleaning thereof. The screen at the entrance end also serves to collect lint and fluff and by removal of the screen, the collected material may also be removed without damage to the ends of the capillary fibers.

Other objects, novel features and advantages of this invention will become apparent from the following specification and accompanying drawings, wherein:

Fig. 1 is a fragmentary perspective view, partially broken away, of a capillary cell embodying the invention;

Fig. 2 is a perspective view on a smaller scale of the complete cell;

Fig. 3 is a fragmentary vertical section of the cell, and

Fig. 4 is a view similar to Fig. 2 illustrating a modification.

As shown in Fig. 1, the capillary cell is contained within a basket or casing 10 having openings at its upper and lower extremities to provide for the passage of air and liquid through the basket. The casing 10 is provided with inwardly directed flanges 11 at each extremity and a coarse grid 12 engages the outer surface of each flange 11. A frame 13 fits over each extremity of the casing 10 to retain the grid 12 in engagement with the flange 11 and the frame 13 is held in place by frictional engagement with the casing 10 or by any suitable fastening means.

A mass or body of oriented capillary threads 14 such, for example, as glass fibers, is arranged in the casing 10 with the fibers running parallel to the side walls of the casing and the ends of the capillary threads at each extremity of the casing extending beyond the plane of the flange 11 except for those capillary threads which are arranged between the two flanges 11. Lacings 15 extend through the capillary threads between the grids 12 in the manner set forth in applicant's U. S. Patent No. 2,139,675.

A wire mesh screen 16 engages the inner surface of each flange 11 and is held in place by any suitable means, (not shown). Each aperture of each screen 16 receives a small group of capillary threads 14, the ends of which project beyond the outer surface of the screen 16 sufficiently for the screen 16 to have a stabilizing effect on the fibers. Adjacent the inner surface of each screen 16 is arranged a layer of capillary threads 17 similar to the threads 14, the threads 17 being arranged in a plane at right angles to the threads 14.

The arrangement just described and illustrated

in Figs. 1 to 3 is the arrangement embodied in a new capillary cell. The arrangement illustrated in Fig. 4 and subsequently to be described is the arrangement embodied in a used capillary cell in which the length of the threads 14 has been reduced by breakage of the ends incident to the use and cleaning of the cell.

The structure of Fig. 4 is the same as that of Fig. 3 except for the fact that the entrance screen 16 is spaced inwardly from the flange 11 and corresponding layer of capillary threads 17 is moved inwardly correspondingly. A bracket 18 mounted on the flange 11 is suitably attached to the screen 16 and spaces said screen inwardly from the flange 11.

For commercial considerations, the cell is so constructed that the casing 10 is square in cross-section and measures 20" on each side with the cell being from 8 to 9" deep. A 2" spacing has been found satisfactory for the intersecting members of the grid 12 and in the cell structure herein disclosed the screen 16 preferably is of $\frac{1}{4}$ " spacing. The screen 16 of definite aperture added to the top and bottom thin transverse layers of capillary threads 17 and the lacings 15 present a very substantial and easily handled capillary cell in which movement of the capillary threads 14 from their original and correct positions is substantially prevented. The apertures in the screen 16 though only $\frac{1}{4}$ " are widely enough separated so that there appears from experimental data to be no increase in the static resistance through the cells. Also, the screens collect the lint and fluff previously collected by the transverse capillary fibers 17 and thus protect the transverse fibers and reduce the possibility of breakage of ends of the fibers 14 in cleaning the cell. The top of the cell can now be brushed off with a stiff brush either by hand or automatically without in any way affecting the main structure of the cell. Another improvement in conjunction with this type of screen is that if nozzles or sprayers supplying water or other liquids to the cells should cease to function properly and project streams of water rather than sprays at the face of the cell, the screen 16 will break the stream into smaller parts and no thick stream of water or liquid can strike the glass fibers to bore holes or break down the structure of the cell itself. Consequently, it is possible to use some water at higher pressures if essential, particularly when the cells are used for dehumidifying purposes. In the event that it is necessary to remove the screen 16 at either end for any purpose, it can be cleaned and pressed back on the strands 14 to take up a relatively similar position as before. Since the cell is of the same construction at either extremity, either stabilizing screen or both can be removed or the cell can be reversed in its position of use if it is found desirable to do so either to obtain a longer life or greater operating efficiency.

I claim:

1. A capillary cell designed to have air and water pass through it in a vertical direction and comprising a tubular casing, a coarse grid at each extremity of said casing, a plurality of vertical capillary threads in said casing substantially parallel with the sides thereof and to the direction of the flow of air and water through the cell, and a small apertured stabilizing screen adjacent to but spaced inwardly from the upper and lower ends of the casing, each small aperture of said screen receiving the ends of a group of said capillary threads at the top and bottom of the casing and maintaining the threads in a vertical position and in a predetermined relation to the direction of the flow of air and water through the cell and spacing the individual groups of vertical capillary threads from one another.

2. A capillary cell designed to have air and water pass through it in a vertical direction and comprising a tubular casing, a coarse grid at each extremity of said casing, a plurality of vertical capillary threads in said casing substantially parallel with the sides thereof and to the direction of the flow of air and water through the cell, a small apertured stabilizing screen adjacent to but spaced inwardly from the upper and lower ends of the casing, each small aperture of said screen receiving the ends of a group of said capillary threads at the top and bottom of the casing and maintaining the threads in a vertical position and in a predetermined relation to the direction of the flow of air and water through the cell and spacing the individual groups of vertical capillary threads from one another, and means for varying the position of the upper relatively small screen relative to the top of the casing.

3. A capillary cell according to claim 1, characterized by a transverse layer of capillary threads adjacent the inner surface of each screen.

4. A capillary cell according to claim 2, characterized by a transverse layer of capillary threads adjacent the inner surface of each screen.
